UNITED STATES PATENT OFFICE

167,981

ATOMIZER

Serge Heftler-Louiche, Paris, France

Application April 30, 1952, Serial No. 19,534

Term of patent 7 years

(Cl. D83—1)

To all whom it may concern:

Be it known that I, Serge Heftler-Louiche, a citizen of France, residing at Paris, France, have invented a new, original, and ornamental Design for an Atomizer, of which the following is a specification, reference being had to the accompanying drawing, forming part thereof.

In the drawing

Fig. 1 is a side elevational view of an atomizer, showing my new design;

Fig. 2 is a top plan view thereof;

Fig. 3 is a bottom plan view thereof; and

Fig. 4 is a front elevational view thereof.

I claim:

The ornamental design for an atomizer, substantially as shown.

SERGE HEFTLER-LOUCHE.
